United States Patent Office

Des. 233,902

Patented Dec. 10, 1974

233,902

TOY VISUAL EFFECT DEVICE

Kenneth S. Marks, 1315 Sandberg,
Chicago, Ill. 60610

Filed Mar. 30, 1973, Ser. No. 346,623

Term of patent 14 years

Int. Cl. D21—01

U.S. Cl. D34—15 A

FIG. 2

FIG. 1

FIG. 3

FIG. 1 is a perspective view of the toy visual effect device;

FIG. 2 is a top plan view thereof; and

FIG. 3 is a side elevational view thereof.

I claim:

The ornamental design for a toy visual effect device, substantially as shown and described.
